UNITED STATES PATENT OFFICE.

HORACE O. CLARK, OF NEW YORK, N. Y.

VEHICLE-WHEEL.

941,976.

Specification of Letters Patent. Patented Nov. 30, 1909.

Application filed July 15, 1908. Serial No. 443,711.

To all whom it may concern:

Be it known that I, HORACE O. CLARK, a citizen of the United States, residing at New York, in the county of New York and State 5 of New York, have invented a new and useful Vehicle-Wheel, of which the following is a specification.

This invention relates to vehicle wheels of that type utilizing springs for the purpose 10 of taking up vibrations and it is more particularly an improvement upon the wheel described and claimed by me in an application filed Mar. 23, 1907, Serial No. 364,176.

The object of the invention is to provide a 15 wheel having a series of elastic spokes arranged in a novel manner for the purpose of absorbing all vibrations resulting from the movement of the wheel over an uneven surface.

With this and other objects in view the invention consists of certain novel features of construction and combinations of parts which will be hereinafter more fully described and pointed out in the claim.

In the accompanying drawings is shown 25 the preferred form of the invention.

In said drawings: Figure 1 is a view partly in side elevation and partly in section of a portion of a wheel embodying the present improvements. Fig. 2 is an enlarged section through a portion of one of the outer spokes and its holding means. Fig. 3 is a transverse section through a portion of a wheel, said section being taken on the line 35 3-3 Fig. 1.

Referring to the figures by characters of reference, 1 designates a hub having annular flanges 2 at the ends thereof, said flanges being connected by transversely extending removable pins 3. This hub is surrounded by an intermediate rim consisting of spaced similar rings 4, 4 connected at regular intervals by removable cross pins 5 which are equal in number to the pins 3 and disposed 40 on the same radii therewith. These rings are held spaced apart by yokes 6 arranged therebetween and having hooked terminals 7 designed to engage the inner edges of the rings 4. Each yoke has an adjusting screw 8 therein loosely extending therethrough and bearing against a segmental pressure foot 9 having a recess 10 therein into which the screw 8 projects although said screw does not engage the wall of the recess. A nut 11 45 is interposed between the pressure foot and the yoke and is engaged by the screw 8.

This nut is of such size that it can not rotate within the yoke and serves to feed the screw against the pressure foot. Each pressure foot 9 is designed to bear against the concave face of the arch or crown 12 of a V-shaped spoke 13 the terminals of which are bent outwardly substantially at right angles as shown at 14. One of these spokes is positioned between every two pins 5 within the 55 rings 4 and the adjoining portions of the spokes extend along substantially parallel lines to the rim 15 of the wheel and the terminal portions 14 of the adjoining spokes extend toward each other and are designed 65 to be fastened to the rim by means of bolts 16 which extend through said terminal portions and through a holding plate 17 which laps them. After the spokes 13 have been secured to the rim 15 in the manner described 70 the screws 8 can be rotated so as to feed through the nuts and against the pressure feet 9, thus forcing said feet against the arches of the spokes 13 and tightening said spokes. By adjusting the screws in this 75 manner the rings 4 can be properly centered within the rim 15.

The foregoing structure constitutes no part of the present invention.

The elastic means utilized for taking up 80 vibrations consists of two series of ogee-curved springs interposed between the rings 4 and the hub 1. The springs of one series, and which have been indicated by the numeral 18, have their end portions provided 85 with eyes 19' which engage the pins 3 and 5 arranged upon the same radius of the wheel so that the line of pressure along the radius of the wheel will intersect the spring in said radius at the center thereof, said springs being disposed at comparatively slight angles 90 to the radii. The springs 19 constituting the other series are provided at their ends with eyes similar to those upon the springs 18 and are arranged at one side of the springs 95 18. These springs 19 are attached at their ends to the pins 3 and 5 but the pins to which the ends of each spring are attached are not disposed in the same radius. Instead, each spring extends from its inner pin 100 3 to one of the pins 5 adjoining the radius in which said pin 3 is located. It will be seen therefore that the springs 19 have their intermediate portions arranged practically tangentially to the flanges 2 and almost at 105 right angles to the adjoining radii of the wheel and obviously therefore these springs 110

19 are of greater elasticity than the springs 18. This arrangement of springs is desirable because it becomes possible to thus obtain a resiliency which is neither too great 5 nor too slight to interfere with the efficiency of the wheel.

What is claimed is:

In a wheel the combination with a rim, a hub, and an intermediate rim; of spokes interposed between and secured to the rims; and parallel annular series of springs interposed between and secured to the hub and

intermediate rim, the points of connection of each spring of one series being disposed on the same radius of the wheel and the points 15 of connection of each spring of the other series being disposed in different radii.

In testimony that I claim the foregoing as my own, I have hereto affixed my signature in the presence of two witnesses.

HORACE O. CLARY
